UNITED STATES PATENT OFFICE.

WILLIAM J. LAUSTERER, OF JAMESTOWN, NEW YORK, ASSIGNOR, BY MESNE ASSIGNMENTS, TO EMPIRE VOTING MACHINE COMPANY, A CORPORATION OF NEW YORK.

VOTING-MACHINE.

1,199,796.

Specification of Letters Patent.

Patented Oct. 3, 1916.

Application filed November 16, 1908. Serial No. 462,835.

To all whom it may concern:

Be it known that I, WILLIAM J. LAUSTERER, a citizen of the United States, residing at Jamestown, in the county of Chautauqua and State of New York, have invented certain new and useful Improvements in Voting-Machines, of which the following is a specification.

My invention relates to improvements in voting machines of the general type of machines described in the Patent 820,802, issued to W. J. Lausterer, May 15, 1906, and has for its object to provide an improved form of straight ticket mechanism and a mechanism for locking out the keys in primary elections and for holding the keys locked under various conditions, together with releasing mechanism for the keys and for the curtain lever; a separate interlock 20 for the various straight ticket keys and a mechanism for resetting the straight ticket keys.

In the accompanying drawings Figure 1 represents a rear elevation of the front plate 25 of the voting machine with the straight ticket voting mechanism and the individual candidate voting mechanism shown thereon. Fig. 2 is an enlarged detail of the mechanism at the lower left hand corner of Fig. 30 1, showing also the resetting and locking bars and the mechanism for operating them. Fig. 3 is a detail in perspective showing one of the straight ticket operating mechanisms and the various parts that coördinate there- 35 with, to release the individual candidate keys. Fig. 4 is a partial detail of the crank for returning the straight ticket keys. Fig. 40 5 is a detail of the interlock between the straight ticket keys. Fig. 6 is a detail in perspective of the mechanism for operating the latch to release the curtain lever. Fig. 7 is an elevation of the mechanism operated by the party levers or releasing knob to unlock the curtain lever.

45 In the accompanying drawings like reference numerals represent like parts.

In Fig. 1 reference numeral 1 refers to the front plate of the machine on which are pivoted the party levers, the rear part of 50 which is shown in Figs. 1 and 3. These party levers have a short shaft 2 extending through the front plate on which is riveted

the crank 3, Fig. 3, there being one of these party levers for each party row of voting devices on the machine. This crank 3 carries thereon a stud 4 which stud passes through the link 5, which link is pivoted at one end to the straight ticket bar 6 on the stud 7 carried on said bar, and at the other end has a cam surface 8 engaged with the 60 anti-friction roller 9 sleeved on the stud 10 carried on the universal bar 11.

The rotation of the crank of the straight ticket key in the direction indicated by the arrow in Fig. 3 will move the bar 6 forward, will draw the cam 8 forward and up, and will raise the universal bar 11 through the engagement of the anti-friction roller 9 carried thereby with the cam 8. This bar 11 is common to all of the party levers and 70 is raised in the same way by any one of them.

The crank 3 on the straight ticket key carries thereon a cam 12, which in the rotation of said crank reacts on the cam 13 75 carried on the latch 14 pivoted on the stud 15. This latch 14 with its left hand end engages with the bar 16 which bar, as will presently be seen, prevents the movement of the individual keys beyond a limited amount 80 until after the party lever has moved far enough to raise the latch 14. Carried on the straight ticket bar 6 at its rear end is an interlocking stud 17, which stud engages with the interlocking blocks 18, 18, carried 85 on the plate 19 on which plate they are supported by the studs 20, 20.

The interlocking blocks 18 are slotted as shown at 21, 21, and the studs 20 pass through these slots, thus holding the blocks 90 18 to sliding movement on the standard 19. The slots 21 are of sufficient length to permit the blocks 18 to travel far enough to permit any one of the interlocking pins 17 to pass between the two adjacent blocks. 95 The pins 17 and the straight ticket bars on which they are mounted are guided at the rear end by the slots 22 cut in the standard 19, with which slots the studs 17 engage. The studs 17 are of sufficient length to extend through the slot 22 and engage with the interlocking blocks 18, 18 beyond. It will be seen that by reason of these studs 17 and interlocking blocks 18, 18, that no two

straight ticket keys can be out of unvoted position at the same time. Because of this interlock no party lever can be operated at all if another party lever is partially operated.

The pins 17 engage with the crank 23, shown in dotted lines in Fig. 1 which crank is thus turned by any one of the party levers against the torsion of the spring 24 shown in Fig. 4. As soon as the voter lets go of the party lever this spring 24 reacts on the crank 23 and causes the resetting of the party lever and straight ticket bar 6 through the engagement of the crank 23 with the stud 17 carried on the straight ticket bar 6, as above described.

In order to prevent a second operation of the straight ticket key that has been operated, or the subsequent operation of any other straight ticket key I provide the universal bar 25, which when released from the position shown in Fig. 1 will drop and cause the locking of all the straight ticket keys on the machine. The mechanism by which this is secured I am now about to describe.

Carried on the straight ticket bars 6 are the latches 26, which latches engage with the individual voting devices 27. The construction and operation of these latches 26 is more particularly described in my Patent No. 1,072,962; granted Sept. 9, 1913, to which reference is hereby made. When the straight ticket key is voted the straight ticket bar 6 moves to the right and rotates the individual voting devices 27. Each of these voting devices has a projection 28 stamped thereon, each of which projections is long enough to engage with a tooth 29 carried on the locking bar 16, and the latch 26 carried on the straight ticket bar 6. When the bar 6 is moved forward by the straight ticket key the latches 26, 26 thereon engage with the keys 27, 27 and rock them forward against the teeth 29, 29 on the bar 16, which in turn drives the bar 16 forward against the latch 14. At the same instant that the bar 16 begins to move forward against the latch 14, the latch 14 is raised by the crank of the straight ticket key 3 acting thereon through its cam 12, so as to release the bar 16 for forward movement. To secure the lifting of the latch 14 in time, the parts are adjusted so that the bar 6 does not drive the keys 27, 27 against the teeth 29, 29 of the bar 16, until the cam 12 has moved far enough to lift the latch 14. For this purpose a limited lost motion or clearance is given to the bar 6, and the crank that operates it. The further operation of these parts by the party lever will unlock all of the bars 16 so as to permit the voting of the keys controlled thereby, and will lock the party levers against further operation in the manner I am now

about to describe. The bar 16 carries a stud 30, which stud when the bar 16 moves forward engages with the bar 31 and moves it forward. This bar 31 is supported on the vertical arms of two bell cranks 32 pivoted on a stationary support 33. The horizontal arms of these bell cranks are connected by the vertically moving bar 34. By means of these bell cranks and the bar 34 that connects them, the bar 31 is held to a parallel movement when driven forward by any one of the straight ticket keys through the stud 30 on the bar 16 operated thereby. Pivoted on the stationary support 33 at 41 is another bell crank 35 having its horizontal arm engaged with the vertically moving bar 34 with which it is connected by the stud 36. When the bar 31 moves forward and the bar 34 rises, the vertical arm of the bell crank 35 moves forward and carries with it the latch 37. This latch is supported at its forward end by the stud 38 carried on the front plate of the machine, with which stud the latch 37 has a sliding engagement by means of the slot 39 cut in the latch 37. This latch 37 has a bent over end with which it engages with the bar 25 at the recess 40 to lock it. When the bar 34 is raised the bell crank 35 is rocked around its center 41 and the latch 37 is driven forward which in turn releases the bar 25. The bar 25 is then free to drop. Carried on the bar 25 are lugs 42 which when the bar 25 is in its raised position will permit the studs 4 to pass thereunder. As soon as the straight ticket key has been operated and released and the party bar returned to its original position by spring 24, the bar 25 drops, and the lugs 42 thereon come immediately in front of the studs 4 on the straight ticket keys, thus preventing the forward movement of the straight ticket bars 6, thus locking them. In resetting these parts the action of the parts is so timed that the interlocking stud 17 will not be disengaged from the blocks 18 until a considerable time after the stud 4 on the party lever that has been operated has been withdrawn from under the lug 42 on the bar 25. For this purpose when the bar 25 is down and the straight ticket bar 6 is fully reset, there will be an interval of about $\frac{1}{8}$ of an inch between the stud 4 on the straight ticket keys and the lug 42 on the universal bar 25. The forward movement of any of the party levers or straight ticket keys will cause its stud 4 to run squarely into the lug 42 on the bar 25, which lug will thus block the forward movement and hold it against operation. The bar 25 also carries the studs 43. One of these studs 43 is provided for each of the latches 14. When the bar 25 drops to lock the straight ticket keys the studs 43, 43 will engage with the right hand end of

70

130

the latches 14, 14, swinging all of said latches down at the right and raising them at the left. This raising of the latches 14 at the left hand end will unlock all of the 5 bars 16 for forward movement, thus permitting the voting separately of any or all of the individual pointers 27 on the machine, which pointers have all been held locked up to that time, except as they were 10 operated by the party lever first operated.

It will be understood, of course, that none of the pointers 27 on the machine can be voted without moving to the right the bars 16 with which said pointers are engaged, 15 and that the bars 16 cannot be moved to the right until the latches 14 have been raised to permit it, and that all of the latches 14 are simultaneously raised to release all of the bars 16 when the bar 25 is dropped.

20 The bar 25 is mounted on studs 44, 44, which studs are supported by the front plate of the machine, and with which studs 44 the bar 25 maintains a sliding engagement by means of the slots 45, 45, with which said 25 bar 25 engages said studs 44. Several of these studs 44 are provided, with each of which the bar 25 engages with a sliding engagement as above described.

The horizontal arm of the bell crank 35 is 30 made purposely long so as to be engaged with the stud 46 carried on the universal bar 11, so that when the universal bar 11 is raised the bell crank 35 will be rocked in the same manner as though a straight ticket had 35 been voted, unlocking the bar 25 and causing all of the latches 14 to be moved to a position that will release the locking bars 16. This bar 11 is moved independently of any 40 of the straight ticket keys by the operation of the releasing lever 61 shown in Fig. 7, which releasing lever engages with the bar 11 at the recess 60 cut therein. By the operation of the releasing lever through this universal bar 11, the individual pointers are all 45 unlocked for separate operation, and all of the party levers are locked against operation, so that thereafter no voting can be done except with the individual pointers.

To insure the resetting of the bars 16 I 50 provide the universal cam bar 47: this bar has saw tooth cams 48 thereon, one for each of the bars 16. Mounted on each of the bars 16 at the left hand end is a stud 49 having the anti-friction roller 50 thereon. When 55 the bar 16 is moved to the right this stud 49 and its anti-friction roller 50 moves to the right with it, but in moving to the right it does not pass out of engagement with the cam 48 immediately above it. When the 60 machine is reset the cam bar 47 will be drawn down by the resetting mechanism of the machine, which resetting mechanism consists of a bar 51, which presses down on the bell crank 52 pivoted at 53, which bell 65 crank 52 as it moves downward engages

with the stud 54 on the bar 47, causing the bar 47 to move down, in which case the cams 48 thereon will engage with the studs 49 on the bars 16 in the manner above described, and will cause said bars 16 to be drawn back 70 to their initial position, shown in Figs. 1, 2, and 3.

When the bar 25 drops after being released in the manner above described, it carries down with it the connecting rod 62, 75 rocking the walking beam 63 around the center 64. This in turn lifts the bar 65 as shown in Fig. 6. This bar 65 is slotted at 67 and 68 and moves up and down on the studs 69 and 70. On these same studs is also 80 carried the bar 71, which bar is provided with similar slots to engage with the studs. On the bar 71 is pivoted the latch 72. Carried on the bar 65 is the stud 73, which stud moves up and down in the slot 74, when the 85 latch 72 is thrown to the left. This permits the bars 65 and 71 to move independently of each other. When the latch 72 is moved to the right to engage with the stud 73 as shown in Fig. 6, the bars 65 and 71 are fastened together and must move in unison. While the latch 72 is in this position the movement of the walking beam will carry up with it both bars 65 and 71. The bar 71 is provided with a cam 75, which engages 90 with the arm 76 and moves it outward. This arm is pivoted at 77 and carries at its other end a pin 78, which engages with the plate 79 carried on the shaft of the curtain lever 80. This releases the curtain lever for its 95 return movement. When the latch 72 is withdrawn from the position shown in Fig. 6, the bar 65 can move upward without the bar 71, and will then have no effect on the latch 76. The universal bar 25 will cause 100 the bar 65 to be operated in this way when the straight ticket is pulled. If the latch 72 is in engagement with the stud 73, the operation of the straight ticket key will unlock the curtain lever, and if the latch 72 is not 105 in engagement with the stud 73, the operation of the straight ticket keys will not unlock the curtain lever. This adjustment is provided so that the curtain lever can be 110 independently unlocked by means of the 115 question pointers.

As shown in Fig. 1, the question key 81 when moved to Yes or No position will raise the sliding locking bar 82. This bar will engage with the pin 83 carried on the rock 120 shaft 84 and rock it upward. On this rock shaft 84 is carried another pin 85, which engages with the latch 86 to lift it whenever a question key is voted. This latch in turn engages with the stud 87 carried on the bar 125 71 causing the bar 71 to lift when any one of the question keys is operated. The lifting of the bar 71 will cause the operation of the latch 76 in the manner above described. If the latch 72 is thrown to the left the curtain 130

lever can be unlocked only by the question pointers or the releasing lever 61 in a manner about to be described.

Connected to the releasing lever 61 is the 5 connecting bar 90. (Figs. 6 and 7.) This bar extends upward and has in its upper end a slot 91 which engages with the stud 92 carried on the bar 71. Through these connections the releasing lever 61 can act 10 directly on the latch 76 to unlock the curtain lever. Through this releasing lever the curtain lever can be released before or after the straight ticket is voted, making it unnecessary to operate the question pointers 15 in case the latch 72 has been thrown out.

Carried on the bar 65 is a lug 93, which is engaged by a lug 94 carried on the side bar 95, by which the bars 65 and 71 are reset by the return of the curtain lever.

20 Mounted on the universal bar 11 is a latch 100 pivoted on the stud 46. This latch is normally pressed forward against the stud 102 carried on the front plate of the machine. When the bar 11 is raised, 25 the latch 100 will move up with it. As the cam 104 passes the stud 102, the latch 100 will move forward, being pressed in that direction by the spring 101. This spring is mounted in pin 101' on bar 11 and presses 30 against pin 102' on latch 100. When the latch 100 is in this position its upper end is in the path of the stud 103 mounted on the bar 95, which bar moves up and down as the curtain lever is moved over and back.

35 The effect of this engagement is to cause the bar 11 to be forced down when the machine is reset. As the stud 103 and the bar 95 on which it is mounted have not reached the end of their travel when the bar 11 has 40 reached the end of its travel, the cam 104 is provided on the latch 100 to force the latch 100 away from and out of engagement with the stud 103. This is done by having the cam 104 react on the stud 102, by which 45 the latch 11 is thrown back out of engagement, leaving the stud 103 and the bar 95 on which it is carried free to move thereafter independently thereof. The object of this is to compel the resetting of the straight ticket keys and bars before the operating 50 lever of the machine has finished the end of its movement, and in advance of the resetting of the individual keys by the resetting bar of the machine through their interlocking straps.

55 The bar 11 will drop back by gravity as soon as the voter lets go of the party lever, and the latch 100 will normally be operated on by the stud 103 only when the voter 60 holds a party lever in voted position at the same time that he throws the operating lever to reset the machine.

When a voter has entered the booth and thrown the lever 80 to close the curtains and 65 unlock the machine the lever 76 is turned

clockwise by gravity around pivot 77 and stud 78 engages a recess in plate 79 and holds the lever 80 against return until lever 76 is tilted counter clockwise. This tilting of lever 76 is accomplished by cam 75 on plate 71 which may be moved either by actuation of a questions key 81 or by turning of the releasing lever 61 or, if latch 72 is in the position shown in Fig. 6, by the lifting of a party lever. The individual candidate keys 75 are released for voting by turning the releasing lever 61 or any party lever. The turning of releasing lever 61 acts through pin 46 to tip bell crank 35 counter clockwise around its pivot 41 moving latch 37 to the right Fig. 1 to drop bar 25 so that lugs 42 are in line of pins 4 of the party levers and hold said levers from movement. At the same time pins 43 on bar 25 engage with latches 14 turning them on their pivots and releasing the locking bars 16. At the same time the tilting of bell crank 35 acts through pin 36 to raise bar 34 and thus move bar 31 to the right out of the way of pins 30. In this way the individual keys are released 80 for voting and the party levers are locked against movement.

If instead of releasing lever 61 a party lever is turned then the corresponding straight ticket bar 6 is pulled to the right 95 by pin 4, latch 14 is released by cam 12 and all the keys of a party line are voted by engagement of latches 26 with lugs 28. Pin 30 on the corresponding locking bar 16 pushes bar 31 to the right releasing latch 100 100 and dropping bar 25, so that one of its lugs 42 will rest on the pin 4 of the party lever operated. Upon release of the party lever, spring 24 draws the party bar 6, link 5 and also the lever back to their original 105 positions moving pin 4 out from beneath lug 42 and dropping bar 25, all of the lugs 42 of which are thus placed in the path of all the pins 4 to lock all of the party levers against voting movement and release all of the individual keys as described in connection with the releasing lever. This bar does not fully drop when latch 38 is released if the party lever is held in voted position, but lug 42 on said bar rests on pin 4 of said 110 lever and the bar will only drop completely when the party lever is released.

Having thus described my invention, what I claim as new and patentable is as follows:

1. The combination in a voting machine of a series of keys arranged in a plurality of party lines, separate straight ticket voting mechanism for each party line for voting collectively all of the keys of any one party line, a separate bar for each party row for holding the keys thereof normally locked, and means co-operating therewith to hold locked all of the keys of the remaining party lines, when the straight ticket oper- 120 125 130

ating means of any one party has been unlocked and moved from its initial position.

2. The combination in a voting machine of a series of voting keys arranged in party lines, a party key for each party line for collectively placing in voted position all the keys of its party line, and locking means, said means including a separate locking bar for each party row of keys normally holding the voting keys against separate voting movement, the party keys being free to be operated, said locking means holding locked against operation all the keys of the other party rows, while the keys of one party row are being operated collectively.

3. The combination in a voting machine of keys arranged in a plurality of party rows, a straight ticket bar for each party row for operating all the keys of its party row, and a locking bar for each party row to lock the keys of its party row, said locking bars holding locked all the keys in the other party rows when the straight ticket bar of any one party row is moved from normal position.

4. The combination in a voting machine of keys arranged in a plurality of party rows, means for locking said keys by party rows, said means including a separate locking bar for each party row of keys, and means for operating said keys by party rows, said locking means normally holding the keys locked until one of the party row operating means has been moved out of and back to normal position.

5. The combination in a voting machine of keys arranged in a plurality of rows, an operating bar and a locking bar for the keys of each row, a latch for each locking bar to hold it in locked position, the operating bar operating to release said latch, and means to prevent the movement of more than one operating bar at a time.

6. The combination in a voting machine of keys arranged in a plurality of parallel rows, an operating bar for the keys of each row, a bar moving longitudinally across the path of movement of said operating bars, for locking all of said operating bars, said bar being normally held out of locking position, and means for releasing said bar on the operation of any one of said operating bars.

7. A key, a bar connected thereto and operated thereby, a locking bar parallel and adjacent and individual to said bar, and a latch to hold it against operation, said key operating to lift said latch to release the bar.

8. In a voting machine, the combination of keys arranged in rows, a locking mechanism and operating devices for the keys of each row, and means whereby the actuation of any of the operating devices will release the locking mechanism and vote the keys of

one row and subsequently release all the locking mechanisms and lock all of the operating devices.

9. A key, a bar connected thereto and operated thereby, a locking bar parallel and adjacent and individual to said first mentioned bar, and a latch to hold it against operation, said key operating to lift said latch to release said locking bar.

10. A series of locking bars, pivoted latches one for each bar, said latches serving to lock the bars against movement, and a bar operating on all of said latches to move them and release the locking bars.

11. A series of locking bars, pivoted gravity latches one for each bar, said latches serving to lock the bars against movement, and a gravity bar operating on all of said latches to rock them on their pivots and release the locking bars.

12. A series of locking bars, pivoted gravity latches one for each bar, said latches serving to lock the bars against movement, a gravity bar, a latch for holding said bar in normal position, a series of party levers, and means operated by any one of said party levers to move the latch and release the gravity bar, said gravity bar operating when released to move the gravity latches and release the locking bars held thereby.

13. The combination in a voting machine of keys arranged in a series of rows, a straight ticket device for operating the keys in each row, a separate locking bar for the keys of each row, said locking bars being capable of movement separately to unlock position to unlock the keys and lock the straight ticket voting mechanism, and means for positively resetting all of said locking bars that have been moved to unlock position.

14. The combination in a voting machine of keys arranged in a series of rows, each of said keys having an arm thereon with an upturned end, and a plurality of bars for directly operating on the upturned end of each of said keys for moving it in different directions.

15. The combination in a voting machine of a series of bars, a stud on each of said bars, a crank bearing on all of said studs to be rotated by any one of them, when its bar is operated, and a spring on said crank to move it in the reverse direction and reset the operated bar.

16. The combination in a voting machine of keys arranged in a series of rows, a separate locking bar for the keys of each row, straight ticket voting mechanism for the keys of each row, said locking bars being capable of movement separately to unlock position to release the keys and lock the straight ticket mechanism, and a cam bar moving across said locking bars and engaging therewith to positively reset all of the

locking bars that have been moved to unlocking position.

17. The combination in a voting machine of keys arranged in a series of rows, sliding bars one for each row, each of said bars operating collectively all the keys of its row, interlocking mechanism between said sliding bars to prevent the simultaneous operation of more than one thereof and means to prevent the operation of all of said bars upon the operation of any one of them.

18. The combination in a voting machine of keys arranged in a series of rows, sliding bars one for each row, each of said bars operating collectively all the keys of its row, a stud carried on each of said bars, interlocking blocks arranged in the path of said studs to prevent the operation at a time of more than one of said studs and its bar, and a plate for supporting said blocks, said plate being slotted to form guides for said studs.

19. The combination in a voting machine of keys arranged in a plurality of rows, an operating bar for the keys of each row, a bar moving across the path of movement of said operating bars, for locking all of said operating bars, said bar being held normally out of locking position, means for releasing said bar on the operation of any one of said operating bars, said bar moving to locking position when the operating bar first operated is reset, means to reset the operating bar, and means to prevent the movement of any other operating bar when the first operating bar is out of normal position.

20. The combination in a voting machine of a series of keys arranged in rows, a locking bar for the keys of each row to hold them locked against operation, and means for unlocking one bar and causing it to move to cause the unlocking of the remaining bars.

21. The combination in a voting machine of a series of keys arranged in rows, a locking bar for the keys of each row to hold them locked against operation, means operating to unlock and move one bar, a stud on each bar, a bar mounted for parallel movement by any one of said studs, and means operated by said bar to cause the unlocking of the remaining locking bars.

22. The combination in a voting machine of a series of keys arranged in rows, a locking bar for the keys of each row to hold them locked against operation, a latch to hold each of said bars in locked position, a releasing bar common to all of said latches to move them and release all of the locking bars held thereby, said releasing bar being normally held inoperative by a latch, and means for moving said latch to release the bar and permit it to unlock the locking bars.

23. The combination in a voting machine of keys arranged in rows, a locking bar for the keys of each row to hold them locked against operation, a latch to hold each of

said bars in locked position, a releasing bar common to all of said latches and capable of operation to move them to release the locking bars held thereby, means for holding said releasing bar inoperative, a bar having a parallel movement and capable of operation by any one of the locking bars, bell cranks connected thereto, a bar moved by said bell cranks, a bell crank connected to said bar and operated thereby, and in turn connected to the means for holding the releasing bar inoperative, whereby the operation of any one locking bar will cause the unlocking of the remaining locking bars, and means to separately unlock and move each of said locking bars to cause the unlocking of the remaining locking bars.

24. The combination in a voting machine of keys arranged in a plurality of party rows, an operating bar and a locking bar for the keys of each row, a latch for each locking bar to hold it in locked position, and a bar capable of moving all said latches to release the locking bars held thereby, said bar also serving when moved to lock all the operating bars against movement.

25. The combination in a voting machine of a series of keys arranged in rows, a separate locking bar and an operating bar for the keys of each row, and means whereby the movement of any operating bar will lock all the other operating bars and release all the locking bars.

26. The combination in a voting machine of a series of keys arranged in rows, a separate locking bar for the keys of each row, and means for holding said bars in locking position, said means being movable to release said bars and permit the independent movement of one or more of said bars.

27. The combination in a voting machine of a series of keys arranged in rows, a separate locking bar for the keys of each row, and means for holding said bars in locking position, said means being movable to release said bars without operating any of the keys on the machine, and permit the independent movement of one or more of said bars.

28. The combination in a voting machine of a series of keys arranged in rows, a separate locking bar and an operating bar for the keys of each row, and means for simultaneously releasing all the locking bars and locking all the operating bars on the machine.

29. The combination in a voting machine of a curtain lever voting mechanism operable to voted position, an operating lever for the machine to reset the voting mechanism, a latch to hold said lever against the resetting movement, and a plurality of means to operate said latch to release the curtain lever for reverse movement.

30. The combination in a voting machine

of voting mechanism operable to voted position, an operating lever for the machine to reset the voting mechanism, a latch to hold said lever against its resetting movement, 5 and a bar movable longitudinally to move said latch, said bar depending for its own operation on the operation of the voting mechanism.

31. The combination in a voting machine 10 of voting mechanism operable to voted position, an operating lever for the machine to reset the voting mechanism, a latch to hold said lever against its resetting movement, question voting mechanism, straight ticket 15 keys, and a releasing knob, and mechanism for operating said latch by either the question voting mechanism, straight ticket keys or the releasing knob.

32. The combination in a voting machine 20 of voting mechanism operable to voted position, an operating lever for the machine to reset the voting mechanism, a latch to hold said lever against its resetting movement, question voting mechanism and straight ticket 25 keys, and mechanism for operating said latch by either the question voting mechanism or the straight ticket keys.

33. The combination in a voting machine 30 of voting mechanism operable to voted position, an operating lever for the machine to reset the voting mechanism, a latch to hold said lever against its resetting movement, question voting mechanism and a releasing 35 knob and mechanism for operating said latch by either the question voting mechanism or the releasing knob.

34. The combination in a voting machine 40 of voting mechanism operable to voted position, an operating lever for the machine to reset the voting mechanism, a latch to hold said lever against its resetting movement, straight ticket keys, and a releasing knob and mechanism for operating said latch by either the straight ticket keys or the releasing 45 knob.

35. The combination in a voting machine 50 of an operating lever for the machine capable of causing the resetting of the machine, a latch to hold said lever against its resetting movement, a slide for moving said latch to release the lever, question voting mechanism and a releasing knob, said slide being operable directly by either the question voting mechanism or the releasing knob of the 55 machine.

36. The combination in a voting machine 60 of an operating lever for the machine capable of causing the resetting of the machine, a latch to hold said lever against its resetting movement, a slide for moving said latch to release the lever, a latch carried on said slide, a second slide mounted adjacent to said first slide and coupled thereto by said latch, and straight ticket voting 65 mechanism for operating through said slides

to move the latch to release the operating lever.

37. The combination in a voting machine of an operating lever for the machine capable of causing the resetting of the machine, 70 a latch to hold said lever against its resetting movement, a slide for moving said latch to release the lever, and a second slide capable of being positively connected to and operating said first slide and separate means 75 for operating each of said slides.

38. The combination in a voting machine of an operating lever for the machine capable of causing the resetting of the machine, 80 a latch to hold said lever against its resetting movement, a slide for moving said latch to release the lever, and means to positively reset said slide.

39. The combination in a voting machine of an operating lever for the machine capable of causing the resetting of the machine, 85 a latch to hold said lever against its resetting movement, a slide for moving said latch to release the lever, and means operated by the resetting lever to positively reset said slide. 90

40. The combination in a voting machine of straight ticket voting mechanism, and a resetting device therefor, and resetting mechanism for the machine operating thereon, said resetting mechanism causing the 95 full movement of the resetting device, and then by its continued movement disengaging itself therefrom to complete its own movement.

41. The combination in a voting machine 100 of straight ticket voting mechanism, a resetting device therefor, and resetting mechanism for the machine, said resetting device operating to cause the full resetting of the straight ticket keys before the resetting 105 mechanism of the machine has reached the end of its movement.

42. The combination in a voting machine 110 of straight ticket voting mechanism, a resetting device therefor, and resetting mechanism for the machine, said resetting device operating to cause the full resetting of the straight ticket keys before the resetting mechanism of the machine has reached the 115 end of its movement, said resetting device being driven by the resetting mechanism of the machine.

43. The combination in a voting machine 120 of straight ticket voting mechanism, of an auxiliary resetting bar therefor, a latch carried on said auxiliary bar and capable of being raised and lowered therewith, a stud against which said latch presses, a spring for pressing said latch forward against said stud, a main resetting bar adjacent to said auxiliary bar, said latch when in elevated position engaging with said main bar, and a cam for disengaging said latch from the main bar, when in its lowest position. 125

44. The combination in a voting machine 130

of keys arranged in a series of rows, a locking bar for the keys of each row, and straight ticket voting mechanism for the keys of each row, said locking bars being capable of movement separately to unlock position to release the keys and lock the straight ticket mechanism.

45. The combination with voting members, party levers for actuating the voting members and a cam bar and connections for locking and unlocking the party levers, of releasing mechanism and connections independent of said voting members and party levers which lock all the party levers, leaving all the voting members unlocked and all the party levers locked.

46. The combination with voting mem-

bers, party levers for actuating the voting members, and means for locking and unlocking the party levers, of interlocking members which prevent a vote for more than one candidate for any office and releasing mechanism and connections independent of said voting members, party levers, and interlocking members which lock the party levers, leaving the voting members unlocked and the party levers locked.

In testimony whereof I affix my signature in presence of two witnesses.

WILLIAM J. LAUSTERER.

Witnesses:

ALEXANDER B. CORCILIUS,
E. C. MILLER.
